UNITED STATES PATENT OFFICE.

EUGENE R. METHUDY, OF ST. LOUIS, MISSOURI, ASSIGNOR TO ALVIN D. GOLDMAN,
OF ST. LOUIS, MISSOURI.

DESIGN FOR A GAS RANGE.

Application filed August 20, 1927. Serial No. 23,161. Term of patent 14 years.

To all whom it may concern:

Be it known that I, EUGENE R. METHUDY, a citizen of the United States, residing in the city of St. Louis and State of Missouri, have invented a new, original, and ornamental Design for Gas Range, substantially as shown in the accompanying drawing.

The figure is a perspective view of a gas range showing my new design.

I claim:

The ornamental design for a gas range, substantially as shown.

EUGENE R. METHUDY.
